UNITED STATES PATENT OFFICE

131,678

DESIGN FOR AN INSIDE MICROMETER

Adolph H. Davis, Cincinnati, Ohio

Application November 7, 1941, Serial No. 104,088

Term of patent 14 years

To all whom it may concern:

Be it known that I, Adolph H. Davis, a citizen of the United States and a resident of Cincinnati, county of Hamilton, and State of Ohio, have invented a new, original, and ornamental Design for an Inside Micrometer, of which the following is a specification, reference being had to the accompanying drawings, becoming part thereof.

Figure I is a front elevational view of the inside micrometer showing my new design.

Figure II is a similar elevational view of the micrometer of Figure I shown in the direction parallel to the micrometer adjusting barrel thereof.

Figure III is an elevational view of the micrometer shown perpendicular to the micrometer adjusting barrel shown in Figure II of the micrometer.

Figure IV is a top plan view of the micrometer shown in Figures I, II, and III.

Figure V is a bottom view of the micrometer shown in Figures I, II, III, and IV.

Fig. VI is a sectional view taken on line VI—VI of Fig. 1.

I claim:

The ornamental design for an inside micrometer, substantially as shown.

ADOLPH H. DAVIS.
